UNITED STATES PATENT OFFICE.

OLIVER L. LINK, OF ST. CHARLES, MISSOURI.

COOLER.

1,205,096.

Specification of Letters Patent.

Patented Nov. 14, 1916.

Application filed November 5, 1913. Serial No. 799,818.

To all whom it may concern:

Be it known that I, OLIVER L. LINK, a citizen of the United States of America, residing in St. Charles, in the county of St. Charles and State of Missouri, have invented certain new and useful Improvements in Coolers, of which the following is a specification.

The primary object of this invention is to provide a cooler which can be readily cleaned and kept in a sanitary condition.

Another object is to provide a cooler that is of a dismountable form, which can be readily taken apart to facilitate the cleaning of all the parts relating thereto.

A further object is to provide improved means in a cooler whereby when the liquid container is lifted from the cooling compartment said container will immediately drain its contents into the drain pipe, and the contents of the cooling compartment will also be drained.

Other and further objects will appear in the specification and be specifically pointed out in the appended claims, reference being had to the accompanying drawings exemplifying the invention, and in which,

Figure 1 is a vertical section taken through this improved cooler. Fig. 2 is a vertical section taken on the line II—II, Fig. 1. Fig. 3 is a plan view of Fig. 1. Fig. 4 is an enlarged fragmentary detail section showing the connection between the container and the draw-off pipe. Fig. 5 is an enlarged fragmentary section taken on the line V—V, Fig. 2. Fig. 6 is an enlarged fragmentary section of a different embodiment of the connection between the container and the draw-off pipe.

Referring to the drawings: 1 designates a casing which surrounds the chamber 2. Said casing is preferably constructed of outer and inner side walls 3 and 4 forming an insulation space 5. The bottom 6 of said chamber is preferably elevated from the base 7, thus forming an insulation space 8 between said bottom and said base. The outer wall 3 of said chamber extends downwardly a distance below the base 7, thus forming a footing for said casing 1. Said casing 1 is adapted to rest on a support 9, said support being secured to the wall 10 by screws 11. Formed on one side of said support 9 is a cup-rest 12. Formed in the bottom of said support 9 and cup-rest 12 is an opening 13, said opening forming into a

funnel-like portion 14. Formed in the bottom of said portion is an outlet 15, which is for the reception of a drain pipe (not shown).

Secured to one side of the inner wall 4 of the casing is a pair of rectangular supports 16, said supports being arranged horizontally and in vertical alinement with each other. Mounted in the bottom 6 and base 7 of said casing is a seat 17, said seat communicating with, and being secured to one end of a draw-off pipe 18. The opposite end of said pipe has secured thereto a faucet 19, said faucet being outside of the casing 1. Adapted to be mounted in said chamber 2 and supported in the rectangular supports 16 is a liquid container 20, said container being open at both ends. The lower end of said container is preferably rounded, as shown at 21, and has secured thereto on the outside a tapering plug 22. Said plug has an opening 23 formed therein which communicates with the interior of the container 20, and comprises a metallic nozzle 24. Said nozzle has formed thereon at its protruding end an annular shoulder 25. Mounted on said nozzle 24 between the shoulder 25 and the base portion 26 of said nozzle is a frustum-shaped gasket 27.

Formed on each support 16 is a bearing 28, said bearings alining with each other vertically, and are for the reception of the handle 29 of a drain plug 30. Said plug is adapted to engage a seat 31 of a drain opening 32, which seat is located in the bottom 6 and base 7 of casing 1. Said plug 30 comprises a tapering nipple 33, preferably made of flexible material, said nipple being secured to the handle 29 by the retaining member 34. The handle 29 is hollow, and formed adjacent the top of said handle is an overflow opening 35.

This improved cooler is designed so all parts of the interior thereof can be made accessible so as to insure thorough cleansing. When it is desired to get this improved cooler ready for use, the container 20 is placed in the cooling compartment 2, firstly, by inserting the rounded bottom 21 in the upper support 16, then lowering said container and said rounded bottom will engage the lower support 16. This engaging of the container in the support 16 will aline the plug 22 with the seat 17. As said plug 110 engages said seat, the gasket 27 will fit tightly in said seat. This connecting of

the plug 22 with said seat 17 provides communication between the container 20 and the draw off pipe 18. Water is then poured into the container 20 from the top, and the 5 lid 36 is then closed over the top opening thereof. Ice is then packed into the chamber 2, and the cover 37 is then mounted on top of the casing 1. As the ice melts in said chamber and the water therefrom rises, the 10 water level will reach the overflow opening 35 in the handle 29. Said water will then drain down said handle through the nipple 33 into the funnel-like portion 14 of the support 9 to the waste or drain pipe.

15 In order to prevent the container 20 from unseating from the seat 17 by reason of the level of the water in said container being lowered and the water pressure in the chamber 2 being increased, leaf springs 38 are 20 secured to said container adjacent the top thereof, and said springs will engage the top support 16 when said container is lowered therethrough. These springs merely serve as a tightening element.

25 When it is desired to clean this improved cooler, the water from the ice in the chamber is drawn off by manipulating the handle 29 and elevating the tapering nipple 33 from its seat. The container 20 is then lifted, 30 thus unseating the plug 22 from its seat 17. If any water is left in said container, said water will drain through the opening 23 of the plug 22 into the chamber 2. Thus 35 all refuse water from the container and from the casing will drain off through the opening 32 into the funnel portion 14 of the support 9 and to the drain pipe. The chamber 2 and drain leading therefrom are then thoroughly flushed out by steam as well as 40 the draw-off pipe 18. When the faucet 19 is left open, the container 20 can also be thoroughly flushed.

45 In order to provide improved means for automatically flushing the drain pipe 18, as shown in Fig. 6, the nozzle 39, which is similar to the nozzle 24, has an extension portion 40. The lower end of said extension portion has mounted thereon a frustum-shaped gasket 41 which is adapted to seat 50 in the seat 42 formed in the fitting 43. Said extension portion 40 has an opening 44 formed adjacent its lower end. In this construction, when the container 20' is elevated, the plug 22' is removed from the seat 17', 55 which movement will also elevate the gasket 41 from the seat 42, and all the water that is in the container will pass out of the opening 44 to the opening of the seat 42, as well

as the water that will be allowed to pass from the cooling chamber through the 60 seat 17'.

What I claim is:

1. A cooler comprising a casing, a support located in said casing, a draw-off pipe leading from said casing having a seat 65 formed at one end, a liquid container adapted to be mounted in said support having a seat engaging portion formed at one end, said container when mounted in said support adapted to have its seat engaging portion engage said seat in said pipe, said support forming means for alining said seat engaging portion of said container with said seat of said pipe, a wedging element carried by said container adapted to engage 70 said support, said wedging element adapted to prevent said container from floating when a liquid is contained in said casing.

2. In a cooler, a casing, a series of horizontally arranged supports mounted in vertical alinement in said casing, a liquid container having a rounded lower end adapted to be supported by said supports, said rounded end of said container providing means for guiding said container into said 80 supports while said container is being introduced in said supports, and a wedging member carried by said container adapted to be engaged between said container and one of said supports, said wedging member 85 providing means for preventing said container from floating out of position when a liquid is contained in said casing.

3. In a cooler, a casing, a series of horizontally arranged supports mounted in vertical alinement in said casing, a liquid container having a rounded lower end, said container adapted to be mounted in said supports, a discharge nozzle secured to the rounded end of said container, a discharge 95 pipe having its receiving end in communication with said casing, a nozzle seat formed in the receiving end of said pipe, said nozzle of said container adapted to be seated in said nozzle seat of said pipe, said rounded 100 end of said container providing means for guiding said container into position in said supports, said rounded end of said container and said supports providing means for guiding said discharge nozzle of said container into said nozzle seat of said pipe.

OLIVER L. LINK.
